UNITED STATES PATENT OFFICE.

TOM PADGITT, OF WACO, TEXAS.

DESIGN FOR A SADDLE-PAD.

SPECIFICATION forming part of Design No. 31,409, dated August 15, 1899.

Application filed July 5, 1899. Serial No. 722,876. Term of patent 14 years.

To all whom it may concern:

Be it known that I, TOM PADGITT, a citizen of the United States, residing at Waco, in the county of McLennan and State of Texas, have 5 invented and produced a certain new and original Design for Saddle-Pads; and I do declare the following to be a full, clear, and exact description of the invention, such as will enable others skilled in the art to which it appertains 10 to make and use the same.

The invention relates to a new and original design for saddle-pads; and it consists of a saddle-pad of the configuration and ornamentation shown in the accompanying drawings, 15 in which—

Figure 1 is a perspective view, and Fig. 2 is a longitudinal sectional view.

The leading feature of the design comprises the sides 1, arranged at angles to each

other and having their upper edges forming 20 an apex which is curved longitudinally and their outer surfaces formed with longitudinal rows of scalloped ribs, above which is a compound-curve swell which merges into the apex formed by the upper edges of the sides. 25 The ends and lower edges of the sides have projecting therefrom scalloped trimmings.

What I claim is—

The design for a saddle-pad as herein shown and described. 30

In testimony whereof I have hereunto set my hand in presence of two subscribing witnesses.

TOM PADGITT.
